ERNEST L. REGUIN, OF SAN FRANCISCO, CALIFORNIA.

SASH-LOCK FOR REVERSIBLE WINDOWS.

1,109,871.

Specification of Letters Patent.

Patented Sept. 8, 1914.

Application filed December 26, 1912. Serial No. 738,534.

To all whom it may concern:

Be it known that I, ERNEST L. REGUIN, a citizen of the United States, residing in the city and county of San Francisco and State of California, have invented new and useful Improvements in Sash-Locks for Reversible Windows, of which the following is a specification.

This invention relates to a sash lock.

10. The object of the present invention is to provide a cheap, simple, substantial sash lock which is particularly designed for attachment to pivoted reversible windows, and which is so constructed that it may be secured in the stile of the window frame, where it is hidden from view, and from whence it may be projected into engagement with locking means on the sash to lock the sash.

20. A further object of the invention is generally to improve this class of sash locking mechanism so as to increase its general applicability, durability and efficiency.

25. The invention consists of the parts and the construction and combination of parts as hereinafter more fully described and claimed, having reference to the accompanying drawing, in which—

30. Figure 1 is a side elevation partly broken away and partly in section, showing the locking bar projected into locking position with relation to the side rail of the window sash. Fig. 2 is a cross section of Fig. 1 on the line V—V. Fig. 3 is a similar section on the line X—X, Fig. 1, showing the window casing in position. Fig. 4 is a section on the line Z—Z, Fig. 1.

35. Referring to the drawings, A indicates in general the stile of a window frame in which a window B is pivotally mounted. The pivot member 2 is here shown as secured to the side rail of the window sash by screws 3, and is suitably journaled, as shown at 4, in a socket member 5, secured in the stile of the window frame. The pivot member 2 may also be provided with suitable means, 40 as the lock nut 6, for the purpose of retaining the parts in relative position.

45. Slidably mounted in a longitudinal slot 7, cut or otherwise formed in the stile of the window frame, is a locking bar 8, which is so mounted that it may be projected into a similar longitudinal slot 9 formed in the face of the side rail of the sash. The position and movements of the locking bar 8 are 50 controlled by an eccentric 10, mounted upon the end of a horizontally disposed shaft 11

suitably journaled in a socket member 12 which projects through the stile or casing of the window, as shown in Fig. 3. The end of the shaft 11 is provided with a square portion 13, upon which is secured a thumb piece or operating lever 14. The operating lever 14 is provided for the purpose of rocking the shaft from one position to another; this rocking movement being transmitted 60 through the eccentric to either project or retract the locking bar.

When applying the locking mechanism here shown to pivotally mounted, reversible windows, it is desirable to allow the slot 9, 70 formed in the side rail, to extend the whole length of the side rail, thus allowing a locking bar of similar length to be projected into engagement with said slot, when the slots register, which takes place when the window 75 has assumed the closed position. This forms a very substantial lock as it locks the whole side of the window. The slot 9 in the side rail of the sash is also provided with cross bars 15, and the locking bar is shown as provided with hook-shaped pocket portions 16 80 which are adapted to be swung into engagement with the cross bars in the slot 9 to form a positive lock between the side rail and locking bar. The upper portions 17 of the 85 pockets 16 are shown as being cam-shaped and will, when thrown into engagement with the cross bars, exert their pressure to draw the side rail into close contact with the stile of the window, thus making a tight joint between the sash and window frame and also preventing any rattling or vibration between the window and frame.

90. For the purpose of insuring a parallel and even movement of the locking bar, when this 95 is projected or retracted, I have provided the segmental slots 18 in the opposite ends of the bar through which the guide pins 19 project. The movement of the bar from the retracted position to the projected position, 100 or vice versa, is controlled, as before stated, by the movement of the eccentric 10 and will, therefore, of necessity become an arcual movement, the radius of which will depend upon the throw of the eccentric around the 105 pivot shaft 11. This arcual movement allows the hook-shaped pockets to be thrown into and out of engagement with the cross bars 15 in the side rail, and also permits the segmental slots 18 to slide from one position 110 to another on the guide pins 19.

While I have here shown the application

of the invention to a pivotally mounted, reversible window, I wish it understood that it is equally applicable to the pulley stile of a sliding sash or double-hung window. The hook-shaped portions 16 engaging with the cross bars 15 will effectually lock the sliding window. It will also be understood that it is equally applicable to either the upper or the lower window.

- 10 The locking mechanism here shown is simple in construction and substantial and reliable in its actions. Its construction also allows its application both to swinging, reversible windows and double-hung windows.
- 15 Being positioned and operable as already described, it is always hidden from view and thus practically insures a burglar-proof lock.

20 The materials and finish of the several parts of the mechanism are such as experience and judgment of the manufacturer may dictate.

I wish it understood that various changes in form, proportions and minor details of 25 construction may be resorted to within the scope of the appended claim, and that I do not wish to limit myself to the specific design and construction here shown.

Having thus described my invention, 30 what I claim and desire to secure by Letters Patent is—

In a window, the combination of a win-

dow frame, a sash centrally pivoted on horizontal pivots to swing in the opening in the frame, a side rail of the sash having, on its 35 face which is adjacent to a side of the frame, a longitudinal slot in the plane of the sash, a locking bar mounted in the open slot in the side of the frame, so as to be projected toward and from the slotted side of the 40 sash, locking hooks formed on the outer edge of the bar, the slot in the sash having keepers engageable with said hooks, said locking bar having a limited lengthwise movement, in its slot in the frame, said bar having seg- 45 mental upper and lower guide slots which extend in a crosswise direction of said bar, guide pins in the frame fitting said slots and permitting a movement of the bar in and out of its slot in addition to its aforesaid 50 lengthwise movement, and an eccentric key turning in the frame and engaging the bar to move it in and out of its slot and to move it lengthwise thereof, to cause said hooks to engage and disengage with the 55 keepers in the sash.

In testimony whereof I have hereunto set my hand in the presence of two subscribing witnesses.

ERNEST L. REGUIN.
